DESIGN FOR A BOTTLE OPENER

Armand M. Guior, New York, N. Y., assignor to Imperial Dania Silver Corp., New York, N. Y.

Application January 8, 1948, Serial No. 143,597

Term of patent 14 years

(Cl. D44—29)

To all whom it may concern:

Be it known that I, Armand M. Guior, a citizen of the United States and resident of the city, county, and State of New York, have invented a new, original, and ornamental Design for Bottle Opener, of which the following is a specification, reference being had to the accompanying drawings, forming part thereof.

Fig. 1 is a side elevation of a bottle opener, according to my design.

Fig. 2 is a front elevation thereof.

Fig. 3 is a rear elevation thereof.

The side of the bottle opener not shown is the same as the side shown and the essential features of my design reside in those portions shown in full lines.

I claim:
The ornamental design for a bottle opener, substantially as shown and described.

ARMAND M. GUIOR.
